UNITED STATES PATENT OFFICE.

CLAUDE W. HUGHES, OF HOUSTON, TEXAS.

PUMPING MECHANISM.

Application filed July 3, 1926. Serial No. 120,352.

This invention relates to new and useful improvements in a pumping mechanism.

One object of the invention is to provide a novel type of support for the walking beam 5 and crank shaft bearings of a well pumping mechanism.

Another object of the invention is to provide a novel type of walking beam specially designed to be mounted on said walking beam 10 bearing.

A further feature of the invention is to provide, in a device of the character described, a novel type of bracket employed.

With the above and other objects in view 15 this invention has particular relation to certain novel features of construction, arrangement of parts and use, an example of which is given in this specification and illustrated in the accompanying drawings, wherein:—

20 Figure 1 shows a fragmentary side elevation of a pumping apparatus, embodying my invention.

Figure 2 shows a fragmentary front elevation thereof.

25 Figure 3 shows a plan view of a type of walking beam employed, and

Figure 4 shows a side view thereof.

Referring now more particularly to the drawings, wherein like numerals of reference 30 designate similar parts in each of the figures the numeral 1 designates a foundation, preferably of concrete. Upstanding from this foundation there is a post 2, preferably consisting of a section of pipe. This post 2 rests 35 on a foot 3, which is anchored in place by a rod 4 whose lower end is embedded in the foundation and whose upper end is fitted through a central bearing in the foot 3.

40 Mounted on the upper end of the post 2 there is a yoke 5 having the upstanding spaced bearings 6, 6, in which the respective ends of the bearing rod 7 work and a walking beam 8 is mounted on said rod. The post 2 is braced by the brace rods 9, 9, 9, arranged in tripod fashion and preferably tubular in form. The 45 yoke 5 has the downwardly diverging studs 10, whose lower ends are reduced to fit within the adjacent ends of the brace rods 9. The lower ends of these brace rods rest on the 50 brackets, as 11, mounted on the foundation 1. Each bracket 11 is secured to its foundation by means of anchor bolts, as 12, the lower ends of said anchor bolts being embedded in the foundation 1 and their upper ends being 55 fitted through the corresponding bracket and

outwardly threaded to receive nuts, as 13. Each bracket 11 has a hook 14, formed thereon, having a sloping face 15 against which the lower end of the corresponding rod 9 rests and there are tie rods 16, 16, 16, formed 60 with eyes at their lower ends, which engage over the hooks 14 and whose upper ends are also formed with eyes which engage through eyes, as 17, carried by the yoke 5. These tie rods are equipped with turn buckles, as 18, 65 by means of which they may be loosened or tightened up to secure the rods 9, firmly between the studs 10, at their upper ends, and the bearing faces 15, at their lower ends. Adjacent the lower end of the post 2 there is a 70 hook 19, set in the foundation 1, and the post 2 has an eye 20 and a tie rod 21 connects said hook 19 and eye 20, said tie rod 21 being equipped with a turnbuckle 22. Beyond the hook 14 each bracket 11 has an inwardly facing bearing face 23 having a greater pitch, or inclination than the pitch of the face 15 and this bearing face 23, has a boss 24 thereon.

Upstanding from the foundation 1 there is another post 25, similar to the post 2, but 80 preferably shorter and mounted on a foot 26, secured to the foundation in a manner similar to the foot 3.

On the top of this post 25 there is a bearing plate 27 formed with a half bearing 28 and a bearing cap 29 is secured on said plate to complete the bearing 30 in which the crank shaft 31 works. On opposite sides of the post 25 there are the hooks 32, 32, which are embedded in the foundation 1, and anchor rods 33, 33, 90 are engaged with the hooks 32, at their lower ends, and their upper ends are fitted through the plate 27 and threaded to receive the nuts 34. The plate 27 has the downwardly diverging bosses, as 35, and tubular brace rods, as 95 36, have their upper ends fitted over said bosses with their lower ends fitting against the respective bearing faces 23 and receiving the bosses 24, of the corresponding brackets 11. Suitable tie rods, as 37, are connected to the plate 27, at their upper ends and their lower ends are formed with eyes which engage over the respective hooks 14 of the corresponding brackets 11 and these tie rods 37 have the turn buckles 38 by means of which 105 they may be lengthened or shortened. The crank shaft 31 has a suitable crank arm 39 connected at one end to the pitman 40, which in turn is connected to the corresponding end of the walking beam 8. The other end of this 110

beam is connected to the pump rod (not shown) in any conventional manner.

The brace rods 9 and 36 are preferably formed of sections, united by means of suitable couplings, as 41, and said brace rods may be lengthened, or shortened by adding a section or detaching one, as desired.

It is to be noted that the brackets 11, employed, are all similar and thus interchangeable. When used to support the brace rods 9 the lower ends of said rods abut against the bearing faces 15 and when used as a support for the brace rods 36, the lower ends of said rods 36 abut against the bearing faces 23.

In Figures 3 and 4 are shown a novel type of walking beam employed. This walking beam comprises a cylindrical bar 41 having vertical end slots 42, 42, to adapt it for connection to a pitman at one end and to a pump rod at the other. The bar 41 is seated or nested in the yoke 43 and is secured therein by means of the clamps 44 which fit over said bar and have flanges 46 which coincide with the flanges 45 of said yoke and the clamp bolts 44 pass through the coinciding flanges 45, 46, carried by said yoke and plates respectively. The walking beam has a transverse bearing 47 provided to receive the usual bearing rod as 7. Adjacent each end of the walking beam there are the collars 48 secured thereon, each collar having lateral eyes 49 and connecting these eyes 49, on each side, are the guy rods 50 which pass over an upstanding central post 51 mounted on the bar 41 and these guy rods 50 are equipped with

suitable turn buckles as 52 by means of which they may be tightened up or loosened.

What I claim is:

1. In a device of the character described a walking beam including a yoke having a seat, a bar having vertical end slots and resting in said seat, clamp plates fitted over the bar, said yoke and plates having coinciding flanges, clamp bolts through said flanges securing said bar to said yoke, a collar adjacent each end of the bar, each collar having lateral eyes, an upstanding central post mounted on said bar, guy rods passing over the upper end of said post and whose respective ends are connected to the corresponding eyes.

2. In a device of the character described, a walking beam including a yoke having a lengthwise groove, forming a seat, a bar resting in said seat, spaced clamp plates fitted over said bar, said plate and yoke having coinciding flanges, clamp bolts through said flanges securing said bar to said yoke, a collar secured on said bar adjacent each end thereof, each collar having lateral eyes, an upstanding central detachable post mounted on said bar between said plates, guy rods passing over the upper end of said post and whose respective ends are connected to the corresponding eyes, and a turn buckle incorporated into each guy rod.

In testimony whereof I have signed my name to this specification.

CLAUDE W. HUGHES.
